UNITED STATES PATENT OFFICE.

WILLIAM H. PAYNE, OF CAMDEN, NEW JERSEY, ASSIGNOR OF ONE-HALF
TO ALVIN WILKE, OF SAME PLACE.

CHIMNEY-CAP.

SPECIFICATION forming part of Letters Patent No. 258,468, dated May 23, 1882.

Application filed February 28, 1882. (No model.)

To all whom it may concern:

Be it known that I, WILLIAM H. PAYNE, a citizen of the United States, and a resident of Camden, New Jersey, have invented certain 5 Improvements in Chimney-Caps, of which the following is a specification.

The object of my invention is to so construct a chimney-cap as to increase the draft of the chimney and counteract the influence of currents of air, which would otherwise cause down-drafts. This object I attain in the manner which I will now proceed to describe, reference being had to the accompanying drawings, in which—

15 Figure 1 is a perspective view of my improved chimney-cap, showing the parts detached from each other; Fig. 2, a vertical section of the same, and Fig. 3 a sectional plan on the line 1 2, Fig. 2.

20 A is a tubular casing of sheet or cast iron, which is intended to be secured in any convenient manner to the upper end of a chimney or stack. In this casing, near the upper end of the same, are formed a series of inclined

25 openings, *a*, from the front edges of which vanes *b* project into the casing, these vanes following the inclination of the openings, and being also inclined in respect to the radial line of the casing, as shown in Fig. 3. The 30 casing A has internal bearings, *d*, for a shaft, *f*, the upper end of which carries a cap, B, from which is suspended by rods *g* a drum, D, the latter inclosing the upper portion of the casing A, but being free to turn with the cap 35 B and shaft *f*.

In the drum D are formed a series of openings, *i*, inclined in a direction the reverse of the openings *a* in the casing A. To the outside of the drum D, in advance of each opening *i*, is secured a bent vane, *m*, and on 40 the inside of the drum, adjacent to the rear edge of each opening *i*, is a radial vane, *n*, both sets of vanes *m* and *n* following the inclination of the openings *i*. The casing A and drum D are open at the top, and the drum is 45 caused to revolve by the action of the wind upon the exterior vanes, *m*, and upon vanes *w* on the cap B.

The smoke and products of combustion rising through the casing A strike the vanes *b*, 50 and are caused to take a spiral course thereby, before escaping from the top of the casing,

any smoke which escapes through the openings being brought under the influence of the revolving vanes *n*, and being thereby thrown upward and discharged through the openings 55 *a*, or through the opening at the top of the drum; or, if upon the lee side of the chimney, the smoke is free to escape from the openings *i* under the influence of the vanes *n*. The vanes *b* on the inside of the casing A effectually prevent what is commonly termed "downdraft," 60 as currents of air entering the openings *a* are prevented by the vanes *b* from striking downward into the casing, and are thrown upward, so as to escape from the open top or mouth of 65 the said casing, thereby forming jets, which induce draft. Currents caused by the vanes *n* of the revolving drum also strike the vanes *b*, and are deflected upward inside the casing A, so as to induce draft. A deflector, *x*, is 70 preferably arranged on the under side of the cap B, immediately above the mouths of the casing A and drum D, so as to facilitate the discharge of the smoke from the space between the drum and cap. 75

I claim as my invention—

1. The combination, in a chimney-cap, of the central fixed casing, A, having inclined openings *a* and internal vanes, *b*, with the rotating drum D, inclosing said casing, and having inclined internal vanes, *n*, all substantially as set forth. 80

2. The combination, in a chimney-cap, of the fixed central casing, A, having inclined openings *a* and internal vanes, *b*, with the rotating drum D, inclosing said casing, and having inclined openings *i* and inclined internal vanes, *n*, as set forth. 85

3. The combination, in a chimney-cap, of the fixed central casing, A, having inclined openings *a* and internal vanes, *b*, with the rotating drum D, inclosing said casing, and having inclined openings *i*, inclined internal vanes, *n*, and exterior vanes, *m*, as specified. 90

In testimony whereof I have signed my name 95 to this specification in the presence of two subscribing witnesses.

WM. H. PAYNE.
